Primary Examiner — Mark A Goodwin(74) *Attorney, Agent, or Firm* — CAIP SERVICE; Xia Li(57) **CLAIM**

The ornamental design for a gas strut support, as shown and described.

DESCRIPTION

FIG. 1 is a perspective view of a gas strut support showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is bottom plan view thereof.

The broken lines in the drawings depict portions of the gas strut support that form no part of the claimed design.
